William Ray Maxwell, INVENTOR

BY Victor J. Evans

ATTORNEY

UNITED STATES PATENT OFFICE

WILLIAM RAY MAXWELL, OF HICKSVILLE, OHIO

PADLOCK

Application filed February 15, 1929. Serial No. 340,149.

This invention relates to padlocks and has for an object the provision of a lock of this type which is simple and durable in construction, reliable and efficient in use, and which, due to its construction, will resist efforts to force the lock.

Another object of the invention is the provision of a lock which will provide a practically unlimited number of key changes due to the character and arrangement of the tumblers, the construction and arrangement of the latter being such as to receive the thrust or strain in an endwise direction, so that the tumblers may be made relatively thin and arranged in compact form.

With the above and other objects in view, the invention further includes the following novel features and details of construction, to be hereinafter more fully described, illustrated in the accompanying drawings, and pointed out in the appended claims.

In the drawings:—

Figure 1 is a view of a lock constructed in accordance with the invention with one section of the case removed and the shackle extension shown in section, the lock being in locked position.

Figure 2 is a like view showing the shackle released.

Figure 3 is an end view.

Figures 4 and 5 are sections taken respectively on the lines 4—4 and 5—5 of Figure 1.

Figure 6 is a top plan view.

Figure 7 is a bottom plan view, and

Figure 8 is a side view of the key.

Referring to the drawings in detail wherein like characters of reference denote corresponding parts, the lock case as shown is formed of a pair of complementary sections 10 which are recessed to accommodate the locking mechanism and which when secured together are provided with openings 11 and 12. The opening 12 is in the form of a socket to receive the short leg of a shackle 13, while the long leg of the shackle extends through the opening 11 into the lock case and is provided with an extension 14.

The major portion of the shackle 13 is round in cross section and the extension 14 is cross sectionally rectangular and is provided

at one end with a socket 15 which rotatably receives the adjacent end of the shackle. The extension 14 has a sliding fit within the case and is non-rotatable and carries spaced pins 16 which engage an annular groove 17 so that a swiveled connection is provided. The extension 14 is provided with an opening 18 which receives a spring 19 and the latter is tensioned to force the shackle outward when said shackle is released.

The shackle extension 14 is provided in one face with a notch 20 having a shoulder 21 at one end and this shoulder is adapted to be engaged by the inclined edges 22 of tumblers or locking plates 23. The tumblers or plates 23 are pivotally mounted upon a stud or bolt 24 which, as shown in Figure 4 of the drawings, also serves to hold the sections of the case together.

The tumblers or plates 23 are substantially triangular in shape and are provided at one corner with a shoulder 25. This last mentioned shoulder is adapted to engage a shoulder 26 provided at one end of the extension 14. The tumblers or plates 23 are forced in a direction to engage the shoulder 21 by means of springs 27.

Any suitable number of tumblers or locking plates 23 may be employed, and as shown in Figure 4 of the drawings these tumblers or locking plates are arranged side by side so that their inclined portions 22 will be seated against the shoulder 21 of the extension 14 when the shackle is in the position shown in Figure 1. The shackle will thus be held against outward movement.

In order to release the shackle a key 27 is provided. This key is formed at one end with a number of steps 28, there being a step for each of the tumblers 23. The key is inserted within the lock through a slot 29 so that the steps engage the locking plates or tumblers. As the key is forced inward the inclined portions 22 will be withdrawn from the path of the shoulder 21 so that the shackle will be released. In order to prevent the shoulders or stops 25 of the tumblers from engaging the shoulder 26 and thus prevent outward movement of the shackle, the key 27 is provided with a shoulder or shoulders 30

which engage the lock case to limit inward movement of the key. Should the wrong key be used in the lock, one or more of the tumblers would be moved pivotally a sufficient distance when the inclined edge 22 is withdrawn from the extension 14 to cause the shoulder or stop 25 to engage the shoulder 26 and thus hold the shackle against outward movement.

In order to hold the shackle against accidental inward movement, the shackle is provided with a groove 31 which is adapted to receive a guide pin 32 carried by the case, and when the shackle is in the position shown in Figure 2, it is necessary to rotate the shackle before the short leg can enter the socket 12. The shackle is also provided with a recess 33 which engages the pin 32 to guide the short leg of the shackle into the socket.

The invention is susceptible of various changes in its form, proportions and minor details of construction and the right is herein reserved to make such changes as properly fall within the scope of the appended claims.

Having described the invention what is claimed is:—

1. In a lock, a case having spaced openings in one wall, a shackle having a long leg slideable and rotatable in one of the openings and a relatively short leg removably positioned within the other opening, a non-rotatable extension having a swiveled connection with the long leg of the shackle, a shoulder provided upon the long leg, spring influenced key operated locking plates engaging the extension to hold the shoulder in locked position, and means included in the locking plates to engage the shoulder and prevent release of the shackle.

2. In a lock, a case having spaced openings in one wall, a shackle having a long leg slideable and rotatable in one of the openings and a relatively short leg removably positioned within the other opening, a non-rotatable extension having a swiveled connection with the long leg of the shackle, a shoulder provided upon the long leg, pivotally mounted spring influenced locking plates engaging the extension to hold the shackle in locked position, and means included in the locking plates to engage the shoulder and prevent release of the shackle.

3. In a lock, a case having spaced openings in one wall, a shackle having a long leg slideable and rotatable in one of the openings and a relatively short leg removably positioned within the other opening, a non-rotatable extension having a swiveled connection with the long leg of the shackle and a shoulder at one side, spring influenced key operated locking plates engaging the shoulder to hold the shackle in locked position, a second shoulder provided upon the extension, and means included in the locking plates to engage said

second shoulder and prevent release of the shackle.

4. In a lock, a case having spaced openings in one wall, a shackle having a long leg slideable and rotatable in one of the openings and a relatively short leg removably positioned within the other opening, a non-rotatable extension having a swiveled connection with the long leg of the shackle and having a recess in one side providing an inclined shoulder, spring influenced key operated locking plates, each of said plates having an inclined edge to engage the inclined shoulder of the shackle extension, a shoulder provided upon each of the inclined plates and spaced from the inclined edge of said plates, and a second shoulder provided upon the shackle extension and adapted to be engaged by the shoulders of the locking plates.

In testimony whereof I affix my signature.

WILLIAM RAY MAXWELL.
